UNITED STATES PATENT OFFICE.

CARL LEONARD AND FLOYD J. THOMPSON, OF FATE, TEXAS.

FLUE-CLEANER.

1,150,376.

Specification of Letters Patent. Patented Aug. 17, 1915.

Application filed August 6, 1912. Serial No. 713,661.

To all whom it may concern:

Be it known that we, CARL LEONARD and FLOYD J. THOMPSON, residing at Fate, in the county of Rockwall and State of Texas, have 5 invented new and useful Improvements in Flue-Cleaners, of which the following is a specification.

This invention relates to the class of flue cleaners and pertains especially to a steam 10 cleaning device used in connection with the cleaning of boiler flues, etc.

An object of the invention is to provide a portable device adapted to be carried from place to place for the purpose of cleaning 15 flues of all dust, soot and sediment that might have accumulated therein.

Another object of the invention is to provide a cleaning device for using the kinetic energy of steam rather than the expansion 20 force.

A further object of the invention is to provide a specially constructed nozzle adapted to be placed at a flue opening to give the steam as it passes therethrough a spiral, 25 winding or whirling motion thereby causing all the soot or dust within the flue to be dislodged and forced out with the escaping steam.

With the foregoing and other objects in 30 view, our invention consists in such details of construction, arrangement and combination of the several parts as will be herein-after fully described and specifically pointed out in the appended claims.

35 In describing our invention in detail, reference will be had to the accompanying drawings wherein like characters denote like or corresponding parts throughout the several parts and in which,

40 Figure 1 is a longitudinal section of the device. Fig. 2 is an enlarged sectional view of the nozzle, and Fig. 3 is an enlarged sectional view of the nozzle end.

In the drawings the numeral 1 designates 45 a nozzle consisting of a shell 2 on the inner side of which are a suitable number of spiral or screw-like projections 3 which begin at the point 4 and widen uniformly so as to narrow the opening at 5 thereby forming a 50 sort of choke-bore. These screw-like projections are either cast with the shell or are made separately and riveted thereto. It is these projections 3 which give the whirling,

screw-like motion to the steam as it leaves the nozzle and the resulting centrifugal 55 force throws the steam against the entire length of the inside wall of the boiler tube, thus sweeping and cleaning from it all soot and other accumulations clinging to said wall.

The lower end of the nozzle 1 is polygonal-shaped at 6 so as to permit it to be tightly screwed by a wrench, to pipe connection 7 which in turn is screwed to the part 8 of the one piece T. The part 9 of the T is 65 adapted to receive a handle, preferably wood, and is slotted at 10 and provided with lugs 11, which are drawn together by means of a bolt of set-screw for securely clamping the handle in place without injury. As the 70 steam is admitted into the inlet part 12 of the T it comes in contact with the rounded face of a plug or stopper 13, thus forcing it up into the nozzle 1.

It will be readily seen that the kinetic 75 energy of the steam is used, which with the great volume made possible by the open construction of the nozzle and the revolving, whirling, screw-like motion similar to the motion of a bullet, when leaving a rifle barrel, the steam is given the maximum cleaning efficiency.

We desire it to be understood that we may make slight changes in the combination and arrangement of parts without departing 85 from the spirit of the invention, provided such changes come within the scope of the appended claims.

Having thus fully described our invention 90 what we claim as new and desire to secure by Letters Patent is:—

1. In a flue cleaner, a tapering nozzle discharging through its larger end, spirally disposed blades connected with the interior wall of said nozzle, said blades being curved 95 transversely, the inner edges of said blades converging from the inlet portion of said nozzle toward the center of the enlarged discharge portion thereof and extending beyond the plane of the end of said nozzle. 100

2. In a flue cleaner, a tapering nozzle discharging through its larger end, spirally disposed blades connected with the interior wall of said nozzle, said blades being curved transversely, the inner edges of said blades 105 converging from the inlet portion of said

nozzle toward the center of the enlarged discharge portion thereof and extending beyond the plane of the end of said nozzle, the inner edges of the blades providing a free 5 unobstructed passage of the steam into the smaller end of the nozzle, the blades being disposed in close proximity at their upper ends to increase the force of the whirling

and rotating steam as it is discharged from said upper end of said nozzle.

CARL LEONARD.
FLOYD J. THOMPSON.
